UNITED STATES PATENT OFFICE.

LEONARD H. HALL, OF ERIE, PENNSYLVANIA.

PORTABLE STEAM-BOILER.

SPECIFICATION forming part of Letters Patent No. 389,073, dated September 4, 1883.

Application filed May 19, 1883. Serial No. 274,405. (No model.)

To all whom it may concern:

Be it known that I, LEONARD H. HALL, a citizen of the United States, residing at Erie, in the county of Erie and State of Pennsylvania, have invented certain new and useful Improvements in Portable Steam-Boilers; and I do hereby declare the following to be a full, clear, and exact description of the invention, such as will enable others skilled in the art to which it applies to make and use the same, reference being had to the accompanying drawings, and to the letters of reference marked thereon, forming part of this specification.

My invention consists in the improvements in portable steam-boilers hereinafter set forth and explained, and illustrated in the accompanying drawings, in which—

Figure 1 is a front end elevation of my improved portable steam-boiler. Fig. 2 is a vertical longitudinal section of the same through the center thereof. Fig. 3 is a cross-section of same on the line α α in Fig. 2, looking in the direction of the arrow.

Like letters refer to like parts in all of the figures.

The objects of my invention are, first, to construct a portable steam-boiler with a circular fire-box inclosed within the body of the boiler in such shape as to avoid stay-bolting and bracing it, as in boilers of this class having rectangular fire-boxes; second, to construct the rear head of the fire-box and the rear head of the boiler of substantially the same size and with a sufficient number of flues therein to amply stay and support them, and thus avoid the necessity of braces and stay-bolts necessarily used in boilers of the ordinary construction; third, to construct the portion of said boiler-shell surrounding the fire-box oval in shape and that portion of the boiler-shell from the rear end of the fire-box to the rear head of the boiler tapering from the fire-box to the rear head.

In the construction of my improved portable steam-boiler shown, A is the portion of the boiler-shell surrounding the fire-box B, which I make oval in shape with the vertical diameter thereof greatest. Within the shell A is placed a cylindrical fire-box, B, the front end of which is securely riveted to the front boiler-head, C, and the rear end of which is provided

with a flue-head, D, securely riveted therein, the location of the fire-box B in the shell A being near the bottom E thereof, so that between the top F of the fire-box and the top of 55 the shell A there is ample water and steam space. Within the portion A of the shell above the water-line G, I preferably place a dry steam-pipe, H, which communicates with the steam-outlet I of the boiler. The front end of 60 the fire-box B, I close with a circular cast-iron front, J, provided with a fire-door, K, and ash-door L. From the bottom of the inner end of the fire-door opening M is a downwardly-projecting horizontal ledge, N, upon which the 65 front ends of the grate-bars O rest, the rear ends of the grate-bars resting upon an angular rear plate, P, adapted to operate as a stop at the rear end of the grate-bars and prevent the fuel from coming into contact with the flue 70 plate or head D and obstructing the lower tiers of the flues Q, the ends of this plate P resting upon and being supported by the curved sides of the fire-box B. The plate P is also provided with small air-openings, p, through which air 75 is supplied from the ash-pit to the gases as they pass into the flues Q. The flues Q are put in in parallel tiers and extend from the rear head or flue-plate, D, of the fire-box B to and through the rear head, R, of the boiler, this 80 head being of substantially the same diameter as the plate D, forming the rear end of the fire-box. From the rear end of the portion A of the boiler-shell to the rear head, R, thereof the shell S of the boiler tapers, until at the 85 head R it is of the same size as the head R, which is circular.

In constructing the boiler I preferably slope the top portion, T, of the shell about twice as much as I do the bottom portion, T', thus leaving room in the lower part of the rear head for a hand-hole, R', (shown in dotted lines,) under the lower tier of the flues Q, the bottom of the shell T' being sufficiently sloping to drain the sediment accumulating therein toward the 95 front end of the boiler, where it is ordinarily blown off. To the rear head, R, I secure a breeching, d, having a door, e, in the rear end thereof, and a chimney-thimble, f, of usual and ordinary construction.

It will be observed that the normal water-line G does not reach to the rear head of the

boiler, but strikes the upper portion, T, of the boiler-shell some distance therefrom, so that the steam space of the boiler is at the front part thereof.

5 Having thus fully described my invention so as to enable others to construct and use the same, what I claim as new, and desire to secure by Letters Patent of the United States, is—

1. The combination, in a portable steam-boiler shell, of an oval section surrounding the fire-box with a section tapering from the rear end of said fire-box section to the rear head of the boiler, substantially as and for the purpose set forth.

15 2. The combination, in a portable steam-boiler, of a shell consisting of an oval front and a tapering rear section with a circular fire-box inclosed within the oval section, the rear end of said fire-box consisting of a flue-sheet of

20 substantially the same size as the rear boiler-

head, and parallel flues connecting said fire-box flue-sheet with the rear boiler-head, substantially as and for the purpose set forth.

3. The combination, in a portable steam-boiler, of a shell consisting of an oval front 25 section and a front head therein having a circular opening the full size of and in which the front end of the fire-box is riveted, and a tapering rear section having a flue-sheet head riveted therein of substantially the same diameter as the circular fire-box, with parallel flues connecting the rear end of the fire-box with the rear head of the boiler, substantially 30 as and for the purpose set forth.

In testimony whereof I affix my signature in 35 presence of two witnesses.

LEONARD H. HALL.
